CLAIM

The ornamental design for a display screen or portions thereof with graphical user interface, as shown and described.

DESCRIPTION

FIG. 1 is a front view of a display screen or portions thereof with graphical user interface in accordance with a first embodiment of the present invention; and,

FIG. 2 is a front view of a display screen or portions thereof with graphical user interface in accordance with a second embodiment of the present invention.

The broken lines showing of a display screen or portions thereof with graphical user interface are for the purpose of illustrating environmental structure and form no part of the claimed design.
